UNITED STATES PATENT OFFICE

142,006

DESIGN FOR A HAT

John C. Marks, New York, N. Y.

Application May 30, 1945, Serial No. 119,815

Term of patent 3½ years

(Cl. D3—13)

To all whom it may concern:

Be it known that I, John C. Marks a citizen of the United States of America, residing in New York, county of New York, and State of New York, have invented a new, original, and ornamental Design for a Hat, of which the following is a specification, reference being had to the accompanying drawing, forming part thereof.

Fig. 1 is a perspective view of a hat showing my new design, and

Fig. 2 is a similar view thereof showing the ear flaps in lowered position and the strings untied.

The opposite sides of Figures 1 and 2 are substantially the same as that shown in the drawing.

I claim:

The ornamental design for a hat, substantially as shown and described.

JOHN C. MARKS.
